Substituted for abandoned application Serial No.
 571,001, January 1, 1945. This application April
 15, 1948, Serial No. 21,280

3 Claims. (Cl. 218—25)

1

This is a substitute for the application on Grommet extending tool, filed January 1, 1945, Serial No. 571,001, now abandoned.

Grommets, made of rather stiff rubber, are often used as insulation or retaining means for electric wire when passed through all sorts of metallic plates or other fixtures. They are usually of round formation and of a diameter considerably larger than the diameter of aperture through which they are passed. Accordingly it is a tedious process to put a grommet within an aperture made in a fixture. Therefore, the principal object of the present invention is to provide a suitable tool by means of which a grommet of the type described may be extended through an aperture and placed in a desired position within a fixture.

A still further object of the present invention is the provision of a tool, substantially of a diameter of an aperture through which a grommet is to be extended, and which tool may be inserted within the aperture preparatory to the extending of a grommet therethrough, which tool may engage the grommet, and extend one end of the grommet through the aperture by proper manipulation of the tool.

With the above general objects in view and others that will appear as the invention is better understood, the same consists in the novel construction, combination and arrangement of parts hereinafter more fully described, illustrated in the accompanying drawing and pointed out in the appended claims.

In the drawing forming a part of this application, and in which like designating characters refer to corresponding parts throughout the several views;

Fig. 1 is a cross-sectional view through a fixture, with a plurality of grommets in position;

Fig. 2 is a side elevational view of the tool;

Fig. 3 is a similar view, with the tool turned 90 degrees;

Fig. 4 is a similar view, with one of the jaws removed therefrom;

Fig. 5 is an enlarged, and elevational view of the tool;

Fig. 6 is an end elevational view of the tool with the grommet in position therein when the grommet is in the process of being extended through a fixture;

Fig. 7 is a side elevational view of the tool, on a reduced scale, passed through a fixture, with a grommet held thereby preparatory to its being extended through the fixture; and

Fig. 8 is a similar view of the tool illustrating

2

its position and action upon a grommet during the process of extension of the latter through a fixture.

Referring in detail to the present drawing there is shown a fixture such as metallic plate 10 having a plurality of apertures 11, with a plurality of grommets 12 extended therethrough and in an operative position in fixture 10. Each of said grommets 12 is substantially of a cylindrical formation and provided with a central bore 13, for passing electric wires therethrough and thereby for either retaining them within fixture 10 or insulating the same therefrom. Transversely and centrally, the grommet has an annular recess 14, with a resulting reduced central shank 15. The marginal portion of fixture 10 adjacent aperture 11 is adapted to fit within recess 14 when grommet 12 is extended through said aperture 11 and in an operative position within fixture 10. Thus said recess 14 effects flange 16, at each end of grommet 12. In order to place grommet 12 within aperture 11 and in an operative position within fixture 10, one of the flanges 16 must necessarily be passed through aperture 11. Ordinarily this is a difficult process due to the fact that diameter of grommet 12 and therefore of flange 16 is considerably larger than the diameter of aperture 11. This problem is enhanced when the grommet is made of a comparatively stiff rubber. To solve this problem the tool constituting the subject-matter of this application was designed.

The tool includes handle 17 and a rigidly affixed thereto shank 18, the latter being of a cylindrical formation, and of a diameter which is somewhat smaller than the diameter of aperture through which a grommet is to be extended, such as aperture 11.

Integrally formed with shank 18 is stationary jaw 19. The body portion of said shank, adjacent the inner end of said stationary jaw 19 is recessed at two diametrically opposite points thereof for defining recesses 20, thereby effecting a reduced lug 21. Receivable within said recesses 20 are leaves 22 of the bifurcated inner end of movable jaw 23. Said leaves 22 remain in a hinged pivotal relation with lug 21 by means of pin 24 which passes through said leaves 22 and lug 21. The two jaws 19 and 23 are substantially of an identical and complementary construction, and when in a closed position, as indicated by full lines in Fig. 2, constitute a continuation of shank 18.

The outer ends of said jaws 19 and 23 are scooped to provide cavity 25. Along the rear

edges of cavity 25 said jaws 19 and 23 are shaved off as shown at 26, the narrower neck portion of cavity 25 being disposed adjacent the outer end of said jaws 19 and 23 as is clearly seen in Fig. 2.

The edge of each of said jaws 19 and 23 adjacent the inner end of cavity 25 is tapered as at 27 for defining a substantially V-shaped slot 28 when the two jaws are in a closed position, as is seen in Figs. 2 and 5.

To extend a grommet through aperture 11 and to its operative position with plate or fixture 10, as illustrated in Fig. 1, the two jaws are first brought to a closed position shown in Fig. 2, and the same are then extended through aperture 11, with shank 18 in said aperture. Thereupon movable jaw 23 is angularly shifted away from stationary jaw 19 upon its pivot 24 to the position shown in dotted lines in Fig. 2. Thereupon one flange 16 of grommet 12 is placed within jaws 19 and 23 so that the same remains within complementary depressions which define cavity 25 when the two jaws remain in a closed position, as illustrated in Fig. 7. When the two jaws thus engage one flange 16 of the grommet, the shank portion thereof remains within the inner enlarged end of recess 26. Thereupon the two jaws are gradually pulled back through aperture 11, and when the pulling force upon the two increases, movable jaw 23 gradually closes completely, squeezing flange 16 remaining within cavity 25, as is seen in Figs. 6 and 8. Further pulling of the tool will gradually extend the same out of aperture 11 and with it flange 16 remaining within cavity 25. During this operation shank 15 gradually shifts within the reduced outer end of recess 26, so that when the two jaws 19 and 23 have been completely withdrawn from aperture 11, by that time shank 15 remains completely out of engagement by the two jaws and out of recess 26, with one of flanges 16 extended to the opposite side of plate or fixture 10.

For the sake of clearness, one flange 16 of grommet 12, in Figs. 7 and 8, has been eliminated, showing shank 15 thereof in cross-section.

To prevent injury to flange 16 which remains within cavity 25 during the extending operation, tapers 27 are provided, because otherwise the sharp edges at those points would tend to pinch the rubber.

While there is described herein a preferred embodiment of the present invention, it is nevertheless to be understood that minor changes may be made therein without departing from the spirit and scope of the invention as claimed.

What I claim as new is:

1. A tool of the character described comprising

a shank having a jaw on an end thereof and a movable jaw hinged to said shank, said jaws being in opposed relation and having concave inner faces co-acting to form a longitudinal cylindrical cavity therebetween, the jaws being constructed with adjacent edges substantially in abutting relation at one side of the cavity when the jaws are closed and having the adjacent edges thereof spaced apart an appreciable distance at the opposite side of the cavity when the jaws are closed.

2. A tool of the character described comprising a shank having a jaw on an end thereof, and a movable jaw hinged to said shank for swinging movement toward and from the first mentioned jaw and to be disposed in closed position is side-by-side relation with said first mentioned jaw, said jaws having concave inner faces in opposed relation co-acting to form a longitudinal cylindrical cavity therebetween adapted to receive therein a head portion of a resilient grommet, the jaws being constructed with longitudinal adjacent edges substantially in abutting relation at one side of the cavity when the jaws are closed to prevent extruding of the grommet from the recess at said side thereof and having the adjacent longitudinal edges thereof spaced apart an appreciable distance at the opposite side of the cavity when the jaws are closed to receive the shank of the grommet therethrough.

3. A tool of the character described comprising a shank having a jaw on an end thereof, and a movable jaw hinged to said shank for swinging movement toward and from the first mentioned jaw and to be disposed in closed position in side-by-side relation with said first mentioned jaw, said jaws having concave inner faces in opposed relation co-acting to form a longitudinal cylindrical cavity therebetween adapted to receive therein a head portion of a resilient grommet, the jaws being constructed with longitudinal adjacent edges substantially in abutting relation at one side of the cavity when the jaws are closed to prevent extruding of the grommet from the cavity at said side thereof and having the adjacent longitudinal edges thereof spaced apart an appreciable distance at the opposite side of the cavity when the jaws are closed to receive the shank of the grommet therethrough, said cavity having a transverse recess between the spaced opposing edges thereof at the rear end of said cavity formed by transversely extending concave portions formed in said edges.
